(57) **CLAIM**

I claim the ornamental design for a drug delivery device, as shown and described.

DESCRIPTION

FIG. 1 is a top perspective view of a first embodiment of a drug delivery device, in accordance with my new design;
FIG. 2 is a front elevational view thereof;
FIG. 3 is a rear elevational view thereof;
FIG. 4 is a right side elevational view thereof;
FIG. 5 is a left side elevational view thereof; and,
FIG. 6 is a top view thereof.
